UNITED STATES PATENT OFFICE.

HOWARD F. WIERUM, OF UPPER MONTCLAIR, NEW JERSEY.

ORE-FURNACE.

1,162,894.

Specification of Letters Patent.

Patented Dec. 7, 1915.

Application filed June 27, 1913. Serial No. 776,128.

To all whom it may concern:

Be it known that I, HOWARD F. WIERUM, citizen of the United States, residing at Upper Montclair, in the county of Essex and State of New Jersey, have invented or discovered certain new and useful Improvements in Ore-Furnaces, of which the following is a specification, reference being had therein to the accompanying drawings.

10 One of the objects of my present invention is to improve upon mechanical reverberatory furnaces, of the McDougall, Wedge, Herreshoff or similar types, and in particular those furnaces which have a large hollow central revolving shaft for carrying the rabble arms, etc., by the application to the shaft itself of burners to be used for heating the ore under treatment.

Another object is to modify the mechanical furnaces, of the types above referred to, by the addition thereto of heating means, capable, on account of the particular location and arrangement thereof, of heating the ore under treatment, at the opportune moment, namely just before, or just after, or just before and just after the rabbling takes place.

A further object is to devise a method for the treatment of ore with flames and agitation, in such a manner as to enable a given amount of heating flame and a given amount of agitation, to produce the largest possible amount of reaction of the ore under treatment, with the other materials present.

35 A further object is to introduce steam into the ore compartment, (or compartments) in such a manner as not to interfere with the proper and desired operation of the furnace, and of the flames above referred to.

This invention has special applicability to a method of recovering sulfur from sulfid ores by the action of a reducing flame preferably in the presence of some steam, and 45 preferably during the agitation of said ore, but can also be used in other connections.

Burners have heretofore been applied to furnaces of some of these types, which burners have been placed, so as to project through the outer wall of the furnace, in such a manner that the flame, projected toward the center of the furnace, namely; toward the central revolving shaft, but this has been found to be open to certain objections, 55 namely since the flame is ordinarily more or less fan-shaped, the ore which is near the central shaft gets very much more heat,

than the ore which is near the periphery of the furnace, and consequently the action is less uniform than is to be desired. This 60 makes it necessary either to overheat the ore near the central shaft, or to insufficiently heat the ore near the periphery of the hearth, or both, and these are both objectionable as making the furnace reactions 65 somewhat different in these two zones. By placing the burners as above stated, this objection is very largely overcome, for the reason that the widest part of the flame is near the periphery of the hearth, and the 70 narrower part of the flame, is near the hollow shaft. Also by this arrangement the flame does not come into contact with the rabbles themselves, which contact is open to the objection that the flame itself produces practically no heating of the ore at the time when it is in contact with the rabble, or rabble arms, so that a material amount of heat is lost by being absorbed by the cooling fluid in the rabble arm. Moreover, 75 the action of the flame upon the rabble arm, causes the latter to burn out more or less, and thereby makes renewals more frequent. The location of the flame in the present application avoids this injury to the 80 rabble arms.

By arranging the burners as above indicated, all portion of the hearth surface, or the ore upon the hearth surface, are successively and uniformly heated, and also 90 by means of this arrangement of the flame, I can impart to the ore on each unit of hearth surface, substantially the same amount of heat, which means that the heat will be very uniformly distributed, and consequently better utilized. By this arrangement of the burners, with respect to the rabbles, or rabble arms, I can impart the heat to the ore, at a particular time, with reference to the stirring action of the rabbles and in this manner I am enabled to heat the ore at exactly the time when a given amount of heat, and a given amount of stirring, will produce a maximum of effect. All this means a considerable 100 economy of fuel, also a considerable decrease in the wear and tear of the apparatus, and the even conditions makes the process operate more smoothly and means an increased percentage of yield from a given 105 amount of ore, and also more ore can be treated per unit of time.

The accompanying drawings represent rather diagrammatically, a furnace

equipped in accordance with the present invention.

In said drawings, Figure 1 represents a vertical section of said furnace, and Fig. 2 5 represents a substantially horizontal plan section taken on the line 2—2 of Fig. 1.

In said drawings 10 represents the interior iron pipe, which forms the hollow shaft, and which is incased with a layer 11 of fire 10 brick in a well known manner.

The openings 12, of which any desired number may be provided, carry suitable rabbles, as illustrated at 13, which may be water-cooled, or air-cooled, in a manner all 15 ready well known to those skilled in the art, and rabbles of this kind are preferably provided in each of the compartments, of which the furnace is constituted.

14 represents a burner, of which a number 20 are preferably provided, in each compartment, as illustrated in Fig. 2, and one set of these burners is preferably placed as indicated in Fig. 2, at a point slightly in advance of the rabble arms (the shaft, burners and rabbles being rotated in the direction of the arrow 15 in Fig. 2). If desired also another set of burners, shown at 16 may be so placed, as to immediately follow the rabble, in order to heat the ore immediately 30 after the rabbling action. These burners of this second set may be of a smaller size and capacity than the burners 14, if desired.

The burners 14 and 16 are connected as 35 illustrated with an air supply 17 and a gas or oil supply 18, both by valved pipes in a manner well understood in the art.

Upon the outside of the furnace I preferably provide a buss pipe 19, through which steam is delivered to the steam inlets 20, 40 which are preferably placed in a tangential manner, as illustrated in Fig. 2, which steam pipes are provided with suitable valves 21, for the purpose of controlling the amount of steam admitted.

45 By means of the tangential arrangement of these steam pipes I can produce a much more thorough action with the apparatus, and not interfere with the flames, when the latter come in front of the steam inlets.

50 As stated above the burners 14 and 15 produce a more or less fan-shaped flame, as indicated at 24, whereby the maximum amount of uniformity of heating of the ore under treatment is possible.

55 Ore is preferably admitted to the furnace through a suitable hopper 25, and the roasted ore is removed through a spout 26, located at the bottom of the furnace.

27 represents an exit pipe for the gases 60 and vapors produced in operating the furnace.

It is to be understood that each of the several compartments or shelves of the fur-

nace may be provided with the burners, although these may be omitted from some. 65 Each burner may be connected to its own air and fuel supply as illustrated, and each burner may be independently controllable, since it may be desired to operate some of the flames highly reducing, and others only 70 very slightly reducing, and some oxidizing.

It is to be noted that while I have shown one particular form of furnace, the invention is applicable to furnaces of various forms, and I do not limit myself to the particular structure of furnace illustrated. 75

By the term "burner" in this specification and claims, I mean the device which is used to deliver the gas or oil, or the gas and air, or the gas and steam, or the oil and air, 80 or oil and steam, or oil, steam and air, to the desired point, to be burned.

The burners may be all so connected as to be controllable by a master valve, or any desired combinations of burners may be connected by several master valves, one of such valves operating the burners of that particular set or combination. Such a combination of burners as those in a given compartment form a combination of burners which lend 90 themselves readily to such an arrangement.

The term "radially" as used in the appended claims is used to designate the manner of locating the burners, as shown, 95 namely, so that the burner tube, having its opening at the end, as is usual with burners of this kind, points toward the circumference of a circle concentric with the shaft which carries the rabbles and burners. It is to be noted that while the burner is shown 100 as having a considerable slope, in order to project the flame downwardly, my invention is not restricted to any particular angle in this respect.

What I claim is:—

1. In a mechanical furnace provided with a revolving shaft carrying a rabble arm, a burner having an opening at its end, carried substantially radially by said shaft, said burner and the flame thereof being out of 110 contact with said rabble arm, and a tangential steam inlet to said furnace.

2. In a mechanical ore furnace, a rotatable central shaft carrying rabble arms, said shaft being provided with burners having 115 flame openings at their ends, said burners being at a small angle in advance of said rabble arms, whereby the ore on the hearth of the furnace is heated immediately before being rabbled.

In testimony whereof I have affixed my signature, in presence of two witnesses.

HOWARD F. WIERUM.
